(57) **CLAIM**

The ornamental design for an image for a portion of a display screen, as shown and described.

DESCRIPTION

The FIGURE is a front view of an image for a portion of a display screen showing our new design.

The broken line showing of the portion of the display screen is for illustrative purposes only and forms no part of the claimed design. The broken line features within the unclaimed portion of the display screen are unclaimed subject matter.

1 Claim, 1 Drawing Sheet
